AUTOMATIC CHOKE

Robert R. Hutchison, Birmingham, Mich., assignor to General Motors Corporation, Detroit, Mich., a corporation of Delaware

Application November 12, 1953, Serial No. 391,555

10

6 Claims. (Cl. 123—119)

The present invention relates to internal combustion engines and more particularly to automatic choke means for such engines.

To facilitate the starting of a cold internal combustion engine, it is advantageous to employ an excessively rich fuel mixture. Such a mixture is usually obtained by closing a choke valve in the carburetor. In order to eliminate the necessity for the engine operator manually actuating the choke valve, means may be provided for automatically adjusting the choke to its proper position. The most common means of accomplishing this is to employ a thermal responsive element that is operatively connected to the choke valve. During cold conditions the thermal element will close the choke valve, but as the engine warms up to its normal operating temperature the choke valve will be opened to allow the use of a more economical fuel ratio. Since the correct setting of the choke valve is primarily a function of engine temperature rather than the air temperature, the thermal element is preferably responsive to the engine temperature. Accordingly, it is proposed to place a tube or stove in the engine exhaust system and connect the stove to the thermal element by a tube. Thus as the exhaust gases heat up the stove, warm air will flow to the thermal element.

It is also proposed to provide baffle means inside of the stove that will greatly increase the amount of heat transferred from the engine exhaust gases to the air in the stove. By increasing the amount of heat in the air the effects of the heat lost by the air when flowing through the tube from the stove to the choke will be minimized. Thus, the temperature of the air is high enough to insure the temperature of the thermal responsive element in the automatic choke being more nearly proportional to the engine temperature.

In the drawings:

Fig. 1 is a cross sectional view of an engine embodying the present invention.

Fig. 2 is an enlarged view of a portion of Fig. 1 to more clearly show the stove for the automatic choke.

Referring to the drawings in more detail, the present invention may be embodied in any suitable engine 10. However, in the present instance, the invention is shown on a so-called V-type engine 10 having two aligned banks of cylinders 12 and 14 angularly disposed in the engine block 16. A pair of heads 18 and 20 having cavities 22 formed therein are secured to the faces 24 on the sides of the engine 10 so that the cavities 22 in the heads 18 and 20 register with the openings formed by the cylinders 12 and 14. These cavities 22 cooperate with the pistons 26 to form combustion chambers 28.

An induction system 30 may be provided on the engine 10 for delivering a combustible charge to each of the cylinders 12 and 14. The induction system 30 includes an intake manifold 32 disposed between the cylinder heads 18 and 20 and having a carburetor 34 mounted thereon. During engine operation air will be drawn

2

downwardly through the carburetor 34 past the fuel jets in the venturi. This will result in the atomization of a liquid fuel which is mixed with the air to form a combustible charge. The charge will then flow past the throttle valve and be discharged into the distribution passages 36 formed by walls 37. The distribution passages 36 will then direct the flow of the charge into the various cylinders 12 and 14.

An exhaust system 38 and 40 may be provided in each head 18 and 20 for removing the burned exhaust gases from the cylinders 12 and 14. Each system 38 and 40 includes a short exhaust passage 41 for each cylinder. The passage 41 extends through the head 18 or 20 to carry the exhaust gases from an exhaust valve seat 42 to an exhaust port 44 in the side of the head 18 or 20. An exhaust manifold 46 may be provided to collect the gases as they are discharged through the ports 44.

In order to control the flow of exhaust gases past the exhaust valve seat 42, a poppet valve 48 may be provided therein. The opening of this valve 48 is timed by means of a cam shaft located below the cam shaft gallery cover 50. A push rod 52 is slidably disposed in a guide 54 with one end thereof riding on a cam and the other end thereof engaging one end of a rocker arm 56. The rocker arm 56 is pivoted on the pin 58 so that outward movement of the push rod 52 will rotate the rocker arm 56 and depress the valve stem 60 and open the exhaust valve 48. When this occurs the gases may escape into the exhaust system and the associated manifold 46. A coil spring 62 concentric with the stem 60 opposes the push rod 52 assembly and resiliently biases the valve 48 toward the closed position.

An exhaust cross-over passage 64 may be provided through the intake manifold 32 to interconnect the two separate exhaust systems 38 and 40. This cross-over passage 64 extends through the intake manifold 32 so as to form a heating chamber 66 that is in heat exchanging relation with the walls 37 of distribution passages 36 of the induction system 30. The opposite ends 68 of the cross-over passage 64 are connected to the exhaust passages 41 by one or more short passages 70. When the engine 10 is cold the thermostatically controlled heat valve 72 in the exhaust manifold 46 is closed. This will cause the exhaust gases to back up in the manifold 46 and be diverted through the cross-over passage 64. This will heat the walls 37 of the induction passages 36. Thus even though there is a tendency for the cold fuel particles to precipitate out of the mixture onto the walls 37 of the passages 36, they will immediately be evaporated by the heat thus insuring the complete vaporization of the fuel mixture in the induction system. When the engine 10 warms up the heat valve 72 will be opened by thermostatic means to allow the exhaust gases to flow directly into the exhaust pipe. Therefore, during normal engine operation there will only be a periodic oscillation of gases through the cross-over passage 64.

To provide an excessively rich fuel mixture during certain operating conditions, choke valve means 74 may be provided in the carburetor 34 anterior to the fuel jets. Thus when the choke valve is closed the fuel-air mixture will be rich but when the valve is open, the normal economical fuel ratio will be obtained. In order to eliminate the necessity for manually adjusting the choke when the engine 10 is cold, a thermal responsive element such as a bimetallic coil spring 75 may be provided in a housing 76 on the side of the carburetor 34. As this element expands and contracts due to heating and cooling thereof, the choke valve will open and close respectively.

Since the air-fuel ratio is more dependent on the engine temperature than the air temperature, means may be provided for making the thermal element responsive to engine temperature. This may be accomplished by heating the interior of the housing 76 with air heated by the engine 10. In the present instance a tubular stove 78 is placed in a hole 80 drilled diagonally through the intake manifold 32 so as to be disposed inside of the heating chamber 66. Thus the air inside of the stove 78 will be in heat exchanging relation with the hot exhaust gases in this chamber 66.

One end 82 of the stove 78 is open to the atmosphere while the other end 84 is closed by a threaded plug 86. A tube 88 may have one end thereof fitted into a hole 90 in the manifold 32 so as to communicate with the closed end 84 of the stove 78. The opposite end of the tube communicates with the interior of the housing 76 for the thermal element. Thus air may enter the open end of the stove and travel upward through tube 88 and into the housing 76 thus heating the thermal element proportional to engine 10 temperature. Convection may be relied on to induce this flow of air into the housing 76, but it is preferable that the interior of the housing be interconnected with the induction system 30 so that the vacuum present in the system will create a positive flow of air.

Although the air flowing through the stove 78 is in heat exchanging relation with the exhaust gases in the heating chamber 66, unless provision is made therefor, there will be a thin layer of stagnate air on the surface of the stove 78 which will materially interfere with the heat transferred to the air in the stove 78. Since the majority of the air that reaches the inside of the housing 76 travels through the center of the stove 78, it is desirable to stir or mix the air flowing through the stove 78 to insure a complete heating of the air. This may be accomplished by equipping the stove 78 with any suitable baffle 92 that will disrupt the flow of air therethrough. In the present instance this baffle 92 comprises an elongated member 94 that extends the length of the stove 78. The member 94 is provided with a spiral fin 96 that engages the inner walls 98 of the stove 78. Thus as the air flows through the stove 78 it will be divided into two columns that are forced to rotate as they progress through the stove 78. This will thoroughly mix or stir the air and reduce the effects of the boundary layer by causing all parts of the air to come in contact with the walls 98 of the stove 78 thus resulting in a more complete heating of the air. Since the heat transferred to the air is greatly increased, the effects of the heat losses suffered when the air flows through the tube 88 will be greatly decreased so that the temperature in the housing 76 will be a closer reflection of the engine 10 temperature.

While the foregoing description and figures have been confined to one embodiment, it will be apparent to those skilled in the art that numerous modifications may be made without departing from the spirit thereof. Accordingly, it is to be understood that the foregoing is to be considered as illustrative only and in no way restrictive, reference being had to the appended claims to determine the scope of the invention.

What is claimed is:

1. In an engine having two aligned banks of cylinders, an induction system for delivering a combustible charge to said cylinders, a separate exhaust system for each bank of cylinders, a crossover passage interconnecting said exhaust systems, choke means disposed in said induction system for controlling the mixture of said combustible charge, a thermal responsive element on said choke means to actuate said choke in response to temperature changes, and a tube having a portion thereof disposed in said crossover passage in heat exchanging relation with the gases therein, and baffle means disposed in said portion, one end of said tube being connected to said thermal responsive element.

2. In an engine having two banks of aligned cylinders, a fuel induction system for delivering a combustible charge

of fuel to said cylinders, choke means in said induction system for varying the fuel mixture, a thermal responsive element connected to said means to actuate said choke means in response to temperature changes, a separate exhaust system for each bank of cylinders, a crossover passage interconnecting each of said exhaust systems, said crossover passage being in heat exchanging relation with a portion of said induction system, a stove disposed in said crossover passage in heat exchanging relation with the exhaust gases, baffle means inside of said stove, and a tube interconnecting said stove and said thermal responsive element.

3. In an engine having two banks of aligned cylinders, a fuel induction system for delivering a combustible charge to said cylinders, choke means in said induction system for varying the fuel mixture, a thermal responsive element connected to said means to actuate said choke means in response to temperature changes, a separate exhaust system for each bank of cylinders, a crossover passage interconnecting each of said exhaust systems, said crossover passage being in heat exchanging relation with a portion of said induction system, a tube disposed in said crossover passage in heat exchanging relation with the exhaust gases, said tube being positioned adjacent said induction system, spiral baffle means in said tube, and a second tube interconnecting one end of said first tube with said thermal element.

4. In an engine having two aligned banks of cylinders, a fuel induction system for delivering a combustible fuel mixture to said cylinders, a thermal responsive choke in said induction system for varying the mixture of said fuel in response to temperature changes, a separate exhaust system for each of said banks of cylinders for removing the hot gases from said cylinders, a crossover passage interconnecting said exhaust systems, a heating chamber formed in said crossover passage in heat exchanging relation with said induction system, a stove disposed in said chamber in heat exchanging relation with said exhaust gases, a spiral baffle disposed in said stove, and a tube interconnecting said stove with said choke means.

5. In an engine having two aligned sets of cylinders, an induction system having distribution passages for delivering a combustible air-fuel mixture to said cylinders, said induction system including choke means for varying said air-fuel mixture, a separate exhaust system for exhausting the hot gases from each bank of cylinders, a crossover passage interconnecting said exhaust systems and forming a heating chamber in heat exchanging relation with said distribution passages, a thermal responsive element operatively connected to said choke means for actuating said means in response to temperature changes, a tube having the first end thereof associated with said element and having the second end thereof open to the atmosphere to allow air to flow through said tube to said element, a portion of said tube being disposed in said heating chamber in heat exchanging relation with said hot exhaust gases, and a spiral baffle disposed inside of said portion of said tube, said baffle being positioned to stir the flow of air through said portion.

6. In an engine having a block with two aligned sets of cylinders therein, a pair of parallel spaced cylinder heads secured to said block, each of said heads registering with one of said sets of cylinders, an exhaust system formed in each of said heads to exhaust the hot gases from said cylinders, an intake manifold mounted on said engine and having distribution passages formed therein to communicate with said cylinders, a carburetor mounted on said manifold to discharge a combustible air-fuel mixture into said distribution passages, choke means on said carburetor adapted to vary said air-fuel mixture, a housing on said carburetor containing a thermal responsive element operatively connected to said choke, a crossover passage positioned in said manifold to interconnect said exhaust systems and form a chamber in heat exchanging relation with said distribution passages, a stove disposed

in said crossover passage adjacent said distribution passages in heat exchanging relation with said exhaust gases, one end of said stove being open to the atmosphere and the other end thereof being operatively connected to said housing by means of a tube, and an elongated spiral baffle disposed in said stove.
